UNITED STATES PATENT OFFICE.

FRANK O. WILKING, OF INDIANAPOLIS, INDIANA.

PHONOGRAPH-RECORD ALBUM.

Application filed October 25, 1919. Serial No. 333,133.

To all whom it may concern:

Be it known that I, FRANK O. WILKING, a citizen of the United States, and a resident of Indianapolis, county of Marion and State of Indiana, have invented a certain new and useful Phonograph-Record Album; and I do hereby declare that the following is a full, clear, and exact description thereof, reference being had to the accompanying drawings, in which like numerals refer to like parts.

This invention relates to a phonograph record album of the loose leaf type, and the main object of the invention is to provide the album with a plurality of individual record receiving pockets wherein the length of the pockets are graduated so that the ends of the pockets provide index spaces for title labels as well as providing various sized pockets for record disks of different diameters.

Another feature of the invention is the novel construction wherein the covers are flexibly attached to a base in a manner similar to the covers of a book, and in providing the base with a novel finger piece so that the album may be readily grasped to remove the same from the storage cabinet or receptacle without the danger of marring or scratching the latter.

The full nature of this invention will be understood from the accompanying drawings and the following description and claims.

In the drawings Fig 1 is a perspective view of the improved album. Fig. 2 is a plan view thereof showing the top leaf cover in open position and the novel construction and arrangement of the individual record pockets. Fig. 3 is an end elevation of the album with parts thereof in section to show the method of securing the pockets to the base and to show the novel finger piece construction. Fig. 4 is an enlarged view of the free ends of several of the pockets and shows the index arrangement thereof.

In the drawings 1 indicates the base of the album, which is preferably constructed of wood or similar light fibrous material, the outer edge of the base being preferably provided with a curved channel or depression 2 so that the fingers may readily grasp the cross bar or finger piece 3 in order to bodily remove the album from the cabinet or other storage receptacle. The opposite sides

of the cross bar 3 are likewise preferably provided with concavities 4, thus providing for the fingers a positive gripping surface on the cross bar. Instead of the finger piece just described any device such as a knob or 60 knobs may be substituted without departing from the spirit of the invention, so long as the knobs or substituted finger pieces do not project beyond the face of the base 1.

The album proper is formed of a plurality of individual record receiving pockets 5, preferably constructed of strips of paper folded upon themselves and bound around the edges with strips of tape 6, for securing together and strengthening the same. The 70 sheets forming the pockets are left separated along one edge to form a mouth 7 for the insertion or removal of a phonograph record 8. To more readily grip the record and remove the same from the pocket, one face 75 thereof is provided with a cutout portion as shown at 9. The end of each pocket 5 is preferably provided with a title label 10, since each of the several pockets is herein shown of greater length than the next adjacent pocket. The labels on all of the pockets thus will be exposed to readily indicate the record contained within each and all of the individual pockets. Herein I have shown the index edge of the pockets provided with 85 columns for the titles on both sides of the records, the artists who are the authors thereof and the number of the record.

The opposite ends of the pockets 5 are provided with flexible extensions 11, preferably of cloth or similar material, the free edges of which project into the slots 12 formed in the inner edge face of the base 1 and extending longitudinally, said extensions being removably secured in these slots 95 by introducing pins 13 transversely through the base member and through the interposed portions of the extensions.

By attaching the pockets to the base in this manner the pockets can be turned or 100 swung open similar to the leaves of a book, so that by selecting any particular record and then turning the pockets above such selection to one side ready access may be had of the pocket for removing the record. 105 By thus graduating the length of the pockets from top to bottom the designating label for the pockets will not only be exposed to view at all times but the graduated pockets are thus adapted to receive records of vary- 110

ing diameters, such as the standard 10 and 12 inch records, and hold the same more securely.

- If desired, cover leaves 14 of heavy card-board or other similiar material are provided at one end with tabs 15 which are hinged or flexibly secured to the remaining portion of the cover leaf and by fixing the tab sections to the base in the rabbits 18 on 10 the opposite outer faces thereof, the leaves 14 will form a cover and protection for the pockets and their contents, the rigidity of the cover leaves protecting the records against casual breakage or injury.
- 15 The pockets are so constructed and attached to the base member that when filled with records, the thickness through the pockets, the records and the covers will be substantially the same as the thickness of 20 the base member 1. With this construction the album not only can be introduced readily into a cabinet or other device for storing the same, but the records are protected from undue compressional strain. By entering the free edges of the covers into the cabinet first and leaving the base portion 1 towards the opening in the cabinet, the cross bar 3, or any other suitable device provided therefor, may be easily grasped when it is 25 30 desired to remove the album from the cabinet.

From the foregoing it will be understood that the cross bar 3 with the depressions 4 and the tabs 15 are so arranged that no part 35 thereof projects beyond the face of the base member 1, consequently there is no projecting part to mar or in anywise injure the doors or walls of the cabinet in which the album is placed, and each of the records is 40 protected from compressional strain and other injuries.

In addition to providing the designating labels at the ends of the pockets, the front folds of each pocket may be provided with 45 a circular opening 16, thus exposing the central portion of the disc which also contains a label designating the title, author and contents of the record. Herein the edges of the opening 16 are shown prefer- 50 ably reinforced with a tape 17.

It will be understood that the novel album described herein, in addition to the novel construction of the base, also provides a ready index to the records contained there- 55 in, more readily and safely secures records of varying diameters, and protects the same from casual breakage and compressional strain.

The invention claimed is:

- 60 1. A phonograph record album including a rigid base member having a depression in one face thereof, a rabbet in each of the adjacent faces of said base and a plurality of longitudinally extending slots in the face 65 opposite the depressed face, means within

said depression adapted to be gripped to remove the album, a cover leaf secured to each adjacent face in the rabbet thereof whereby no part of said leaf covers and gripping means extends beyond the outer face of the 70 base member, and a plurality of record receiving pockets, each having one edge secured in one of said longitudinal slots.

2. A phonograph record album including a base member having a grooved channel 75 in one edge, a finger-bar secured in said channel, the opposite faces of said finger-bar having gripping surfaces, and a plurality of record-receiving pockets secured to the base member.

80 3. A phonograph record album including a base member having a channel in one edge of the base member, and means located within said channel but not extending beyond said face adapted to be gripped to remove 85 the album.

4. A phonograph record album including a base member having a depression on one face thereof, a longitudinally extending rabbet in each of the adjacent faces of said base, 90 means located within said depression and adapted to be gripped to remove the album, and a cover leaf secured in each of said rabbits, said gripping means and leaf covers having no part extending beyond the outer 95 faces of the base member.

5. A phonograph record album, including a slotted base member, a pair of covers secured to said base, a plurality of disk-record receiving pockets progressively increasing in 100 length and each having a flexible connection seatable in the slotted base, whereby said pockets are secured in spaced relation with each other, each pocket having its increased and exposed end appropriately ruled 105 and provided with a plurality of spaces, one space being adapted to receive the title of the selection of the record contained within the pocket, a second space adapted to receive the name of the artist who is the author of 110 the contained record, and a third space being adapted to receive the number of the record, said spaces registering with each other to form columns for simultaneously exposing the aforesaid data for all the pockets when 115 the top cover is opened, said covers being at least equal in length to the longest record pocket.

6. A phonograph record album, including a slotted base member, a pair of covers 120 secured to said base, a plurality of disk-record receiving pockets progressively increasing in length and each having a flexible connection seatable in the slotted base, whereby said pockets are secured in spaced 125 relation with each other, each pocket having its increased and exposed end appropriately ruled and provided with a plurality of spaces, one space being adapted to receive the name of the artist who is the author of 130

- the contained record, another space for the title of the selection on the reverse side of the record, and another space adapted to receive the number of the record, said spaces 5 registering with each other to form columns for simultaneously exposing the aforesaid data for all the pockets when the top cover is opened, said covers being at least equal in length to the longest record pocket.
- 10 7. A phonograph record album including a base member having a plurality of longitudinally extending slots in one face thereof, a plurality of record receiving pockets progressively increasing in length, a flexible extension for each record receiving pocket and receivable by one of said slots,
- 15 said slots maintaining said extensions in relation with each other to maintain said pockets in substantially the same relation, means extending transversely of said longitudinal slots and seatable in said base for engaging said flexible extensions to secure said pockets in said base, said base being suitably cut away at opposite sides, and cover means seatable in each of said cut-away portions and extending in substantially parallel relation with said pockets and of sufficient length to cover said pockets. 20 25
- In witness whereof, I have hereunto affixed my signature.

FRANK O. WILKING.
